Attorney

UNITED STATES PATENT OFFICE.

ARCHIBALD K. KESSLER, OF HUNTINGTON, WEST VIRGINIA.

EMERGENCY KIT.

Application filed March 2, 1926. Serial No. 91,748.

This invention relates to improvements in containers or kits, and particularly to an emergency kit for containing medicines and medical supplies.

5 An object of the invention resides in providing a device of the above mentioned character having a pair of container sections forming longitudinal half sections in which the edge portions interfit in predetermined relation and which are formed in a predetermined manner for hinged cooperation to provide a kit which when opened, will present the entire interior of each section so that ready access may be obtained 10 to articles secured therein.

20 A further object of the invention resides in providing a kit having a pair of longitudinally arranged half sections hingedly connected and cooperating in a special manner in which each section is provided with suitable means for retaining articles in a predetermined position therein.

25 The invention further comprehends the provision of a pair of half casing sections in which the walls of one section mount suitable hinged retaining members adapted to divide the section in closed relation therewith, into a plurality of compartments, and which may be moved to an open position 30 on the hinged mountings therefor, to provide access to the material therein.

35 A still further object of the invention resides in providing a container having a pair of half longitudinal sections hinged together at one free edge in which a plate member is mounted in one section and suitably formed with cooperating spring clips adapted to receive and grip medicine containers therein, in order that a plurality of 40 these containers may be mounted in closely adjacent relation.

45 The invention comprehends numerous other objects and improvements in the details of construction and arrangement of the parts, which are more particularly pointed out in the following detailed description, and in the claim directed to a preferred form of the invention, it being understood, however, that various changes 50 in the size, shape and relation of these parts may be made without departing from the spirit and scope of the invention as herein set forth.

55 In the drawing forming part of this application:

Figure 1 is a view of the improved emer-

gency kit having the sections arranged in open relation ready for presenting the contents for use.

Fig. 2 is a vertical transverse section 60 thru the kit with the sections in closed position:

The improved emergency kit includes a pair of sections 1 and 2 which form longitudinally extending container sections 65 adapted to cooperate along their free edges in closed position as shown in Fig. 2. The free edge of the section 1 is rolled as indicated by the numeral 3 throughout the entire section, and along one longitudinal 70 edge is provided with a series of spaced slots 4 which receive the circumferential projecting tongues 5 on the adjacent free edge of the section 2 for providing a hinged connection between the sections 1 and 2. 75 The circumferential projections 5 from the section 2 extend outwardly around the rolled edge 3 of the section 1, and then inwardly through the slots 4 and are then curled back toward the free edge of the 80 section 2 from which they extend.

The longitudinal edge of the section 2 opposite the hinged connection and the ends are formed with outwardly swaged edge portions as indicated at 6 to provide 85 a seat 7 for receiving the rolled edge 3 of the container section 1. A handle 8 is suitably attached to the section 2 which also carries a lock member 9 adapted to receive the projections 10 on the section 1 for locking 90 the two sections in closed relation as shown in Fig. 2.

A retaining plate 11 is mounted in the closed end of the section 1 on the inside thereof as clearly shown in Fig. 1, and extends throughout the entire closed end of this section, and is attached by spot welding or in any other suitable manner. This retaining plate is formed in any suitable and desired manner with a plurality of retaining 95 clips 12 for receiving and holding tongue depressors, thermometer cases, and the like, while at 13 the retaining plate is formed with a plurality of pairs of resilient clips of arcuate form arranged in staggered relation and alined longitudinally in rows as clearly shown in Fig. 1 for receiving and mounting a plurality of medicine containers 100 14 arranged in closely associated and alined relation across the face of the plate 11.

110 A pair of compartment forming frame members 15 are hingedly mounted at 16 in

the end of the container section 2, and the free edges are formed with laterally directed flanges 17 disposed toward the bottom or closed end of the container section 2 for cooperation therewith, to divide the container section 2 into a plurality of compartments. In the closed position of these frames 15, a compartment is formed within each frame which is closed by the movement of the frame into cooperation with the container section 2, while an intermediate compartment is formed between the flanges of the frame at opposite ends of the central portion of the container section 2, in which a pair of resilient clips 18 are adapted to retain suitable material positioned therein.

With an emergency kit constructed as illustrated in the drawing and above described, it will be understood that when the two sections, 1 and 2 are in closed position as shown in Fig. 2, a substantially tight container is formed which will exclude dust, water, and other foreign matter under normal conditions, and retain the contents in a substantially clean sterile condition for immediate use upon emergency by opening the sections to the position shown in Fig. 1.

With the kit open as shown in Fig. 1, immediate access is had to all of the material within the kit by moving the compartment forming frames 15 into open position as shown in dotted lines at the right hand side of Fig. 1, which will provide access to the

entire contents of the kit. The entire kit structure is formed of sheet material, suitably stamped and bent to provide the hinged structure, the interfitting edges and the clip structure. The retaining plate 11 extends from a single piece of material and the clips formed in rows arranged in staggered relation to provide material for the formation of the deep clip, and to mount containers therein in close relation in order that a maximum number of medicine containers may be mounted in a small space.

Having thus described my invention, what I claim as new is:

An emergency kit, comprising a container formed of a pair of hinged container forming half sections, means for releasably locking said sections in closed container forming relation, and a pair of rectangular frame members hingedly mounted in the opposite ends of one section and movable toward each other to closed position, each frame member having a plate member formed with laterally extending flanges on the sides adapted for cooperation in the closed position of the members with the ends of the section for dividing said section into a plurality of compartments, and in the open position of the members to provide communication between the several portions of the section.

In testimony whereof I affix my signature.

ARCHIBALD K. KESSLER.
